ATTACHABLE POLARIZED INNER WINDOW FOR CONVEYANCES SUCH AS AIRCRAFT VEHICLES

G. Kurt Davidyan, Gladwyne, Pa., and Richard W. Kraus,
Claymont, Del., assignors to American Polarizers, Inc.,
Reading, Pa.

Filed June 4, 1973, Ser. No. 366,661

Term of patent 14 years

Int. Cl. D12—16

U.S. Cl. D12—183

FIG. 1.

FIG. 5.

FIG. 2.

FIG. 6.

FIG. 3.

FIG. 4.

FIG. 1 is a front elevational view of an attachable polarized inner window for conveyances such as aircraft vehicles showing our design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof.

We claim:

The ornamental design for an attachable polarized inner window for conveyances such as aircraft vehicles, as shown.
